DESIGN FOR A DRINKING GLASS PROTECTOR

John C. Gambell, Oakland, Calif.

Application November 19, 1934, Serial No. 54,082

Term of patent 3½ years

To all whom it may concern:

Be it known that I, John C. Gambell, a citizen of the United States, residing at Oakland, in the county of Alameda and State of California, have invented a new, original, and ornamental Design for a Drinking Glass Protector, of which the following is a specification, reference being had to the accompanying drawing, forming part thereof.

Referring to the drawing, Figure 1 is a diagrammatic plan view of the drinking glass protector showing my design in unfolded position. Figure 2 is a perspective view thereof shown folded to receive a drinking glass.

I claim:

The ornamental design for a drinking glass protector, as shown and described.

JOHN C. GAMBELL.
